BY

Mary F. Ordway
ATTORNEY

UNITED STATES PATENT OFFICE.

WILLIAM SCHMITZ, OF NEW YORK, N. Y.

AUTOMATIC BURNER TIP.

Application filed April 28, 1923. Serial No. 635,213.

To all whom it may concern:

Be it known that I, WILLIAM SCHMITZ, a citizen of the United States, residing at New York, in the county of New York and State of New York, have invented certain new and useful Improvements in Automatic Burner Tips, of which the following is a specification.

This invention relates to gas burners, and 10 has for its object to provide a safety device therefor, whereby, when the gas flame becomes extinguished, the flow of gas will be automatically stopped.

With this object in view, my invention 15 consists in the provision of a thermostatic means in the burner tip and of a valve controlling the flow of gas through said tip and adapted to be automatically acted upon by said thermostatic means, so that the latter, when the gas flame is extinguished, will 20 permit the valve to close, or when the flame is on, will hold the valve open.

I am aware of the several patented devices 25 designed for the same object, but to my knowledge, owing to the nature of their construction, they are objectionable because of their comparatively high cost of manufacture and impracticability. On the other hand, my novel device, not only is very simple 30 in construction, and can be manufactured at very small cost, but can be used with perfect safety.

In the following, I shall describe two 35 forms of construction, of which the first is the preferred form. It being, however, obvious that many changes can be made in the device without departing from the principle of my invention, I do not wish to restrict myself to the details shown and described.

40 In the accompanying drawing, in which similar reference characters denote corresponding parts, Fig. 1 is a longitudinal section of the gas burner equipped with my device; Fig. 2 is a longitudinal section at 45 a right angle to the one of Fig. 1; Fig. 2^a is an elevation of the thermostatic element; Fig. 3 is a cross section on line 3—3 of Fig. 2; Fig. 4 is a similar section to Fig. 2, showing the valve open; Fig. 5 is a perspective 50 view of a detail of the device; Fig. 6 is an elevation of the burner equipped with the device slightly modified in construction and Fig. 7 is a longitudinal section of the gas burner of said modified safety device.

55 Referring to Figs. 1 to 5, in which the preferred form of construction of my device is

illustrated, *a* denotes the burner tube and *b* the hollow burner tip of usual construction fitted snugly in the upper end of the burner tube. The device comprises a cup shaped member 10 adapted to be stationarily supported in the bottom of the hollow tip, as by friction or otherwise. This cup is formed in its center with an opening 11, serving as gas passage and with diametrically opposed upright arms 12, each composed of two metallic strips of different thermostatic properties, so as to bend inwardly or toward one another, when heated by the gas flame, and outwardly or away from one another, when 60 the flame is extinguished. The free end 12' of each arm is curved inwardly and downwardly and terminates in a broadened portion 12² (Figs. 1, 2 and 2^a). These ends normally, i. e. in a cool state, are separated a 65 certain distance, but under the influence of heat are adapted to close like the jaws of a pair of pincers. 13 denotes a member preferably punched out from a blank or piece of thin sheet metal into a substantially 70 oval loop. The upper part 13' of said loop serving as head piece is adapted to movably fit in the slot *b'* of the burner tip and to be rectilinearly guided therein by lateral guide 75 grooves or slots 13², formed on its inner 80 cross edge and spaced apart a distance equal to the diameter of the tip, each slot in width being equal to or slightly larger than the thickness of the circumferential wall of the tip *b*, so as to slidably engage said wall. The 85 central part of said head piece 13' has a downwardly or inwardly directed extension 13³ of reduced width forming a stem extending in the same plane as the body portion of said head piece and adapted, when the cup 10 and loop 13 are mounted in the tip, to pass 90 through the gas passage 11 with sufficient clearance as not to obstruct the passage of gas therethrough. The lower or outer end of said stem is formed to a valve by fixing 95 to it a gasket 14 consisting of washers of suitable material and fixed in position, as by bending over the extreme end of the stem, as at 13⁴ or otherwise. Said valve serves to 100 control the flow of gas through said gas passage 11. Mounted around the stem and resting at one end in the bottom of the cup 10 and at its other end against the shoulders 13⁵ formed at the sides of the stem, is a spiral 105 spring 15, which has the tendency to move the loop and thereby the valve upwardly, whereby the gas passage 11 becomes closed.

The part 13° of the loop below the head piece is bent laterally, so that, when the parts are assembled in the burner, it will extend outside of the latter embracing a portion 5 of the outer face of the gas burner. The lower end of said loop is perforated as at 13° for the attachment of a chain 16 or the like, whereby the valve may be operated from the outside, when it is desired to ignite 10 the gas jet.

In operation the valve, under the action of the spring 15, holds the gas passage 11 closed. In this position, the loop 13 occupies its uppermost position with its head 15 piece 13' extending through the space formed between the two thermostatic arms 12, the latter being then separated or bent away from each other, as heretofore stated. When it is desired to ignite the gas, the member 20 or loop 13 is pulled down by means of the chain 16, thereby pushing the valve down and opening the gas passage 11. The gas flame will cause the thermostatic arms 12 instantaneously to bend inwardly with their 25 broadened ends closing over the outer edge of head piece 13' of the loop 13 and thereby holding the latter and consequently the valve 14 down against the action of the spring 15. On the extinguishment of the gas flame, the 30 thermostatic arms under the changing temperature will bend away from each other and release the loop 13, thereby permitting the spring 15 to thrust it upwardly, closing the valve.

35 In the modification, shown in Figs. 6 and 7, the lower looped part 13° of the member 13 is omitted and the chain is attached to the side flaps 13° extending outwardly through the slot b' of the tip b. Instead of two 40 thermostatic arms, only one may be used, as shown in Fig. 7.

What I claim is:—

1. In a safety device for gas burners, the combination with a standard gas tip, of 45 thermostatic means supported within said tip and a manually operable valve in said tip for controlling communication between said burner and said tip and capable of being automatically controlled by said thermostatic means.

2. In a safety device for gas burners, the combination with the gas tip, of a thermostatic means stationarily supported in said tip, a manually operable resilient member 55 movably borne in said tip and extending outwardly through its mouth, a valve on said member for controlling communication between said burner and said tip, said thermostatic means being adapted, on ignition 60 of the gas jet, to engage said member and thereby hold the valve open, and on extinguishment of the flame to release said member and permit said valve to close.

3. In a safety device for gas burners, the 65 combination with the burner tip, of a mem-

ber fixed therein and formed with thermostatic elements, a spring actuated manually operable valve for controlling communication between said burner and tip, said valve being formed with a member extending 70 through said tip and through the path of said elements, so that, when the gas burns, said thermostatic elements will engage said spring actuated member to hold the valve open and on extinguishment, the flame will 75 release said member and permit the valve to close.

4. In a safety device for gas burners, the combination with the burner tip, of a member fixed in position in said tip and formed 80 with oppositely arranged thermostatic arms, a manually operable member extending through said tip between said arms and resiliently supported on said first member and a valve formed on the outer end of said member, adapted to control communication between said burner and tip, said thermostatic elements being adapted, when heated, 85 to engage said manually operable member to hold said valve open and when cooled, to 90 release the same to close the valve.

5. In a safety device for gas burners, the combination with the burner tip, of a cup shaped member stationarily mounted therein and formed with oppositely projecting thermostatic arms, said cup shaped member having a gas passage, a member movably mounted in said tip and resiliently supported in said cup, a valve formed on said member 100 to close said gas passage, said member being adapted to extend between said thermostatic arms, so that, when heated, said arms will close over said member and hold the valve open, and when cooled, release 105 said member permitting the valve to close.

6. A safety device for gas burners, comprising a pair of oppositely working rigidly connected thermostatic arms, adapted to be 110 stationarily mounted in the gas tip and a looped member resiliently supported between said arms and having a stem extending through said tip and the lower end of which is formed to the valve, the upper end of said member being adapted to be 115 acted upon by said arms and to be operable from the outside of said burner.

7. A safety device for a gas burner, comprising a cup shaped member having a central opening formed with two oppositely 120 acting thermostatic elements, a member formed with a stem adapted to project with one end through said opening and with the other end between said elements, a spring supported in said cup around said stem to normally project said member upwardly 125 through the space between the free ends of said elements, a valve formed on the outer end of said stem to close said opening, and means connected to said member for the manual operation of said valve.

8. In a safety device of the character described, a member punched out of sheet metal to form an angularly bent loop, lateral guide grooves and a centrally and longitudinally extending tongue or stem.
9. In a safety device of the character described, a cup shaped piece formed with an opening in its bottom and two diametrically opposed arms, extending from the marginal edge of said cup, said arms being of bimetallic material of different thermostatic properties.
10. In a safety device for gas burners, a standard gas tip, thermostatic means connected with said tip and a valve movably
11. In a safety device of the character described, the combination with a standard gas tip, of a valve for controlling the flow of gas borne within said tip. 20

In testimony whereof I affix my signature in presence of two witnesses.

WILLIAM SCHMITZ.
